DESIGN FOR A SIDE VIEW MIRROR OR SIMILAR ARTICLE

Lowell F. Sarnes, Dearborn, Mich., assignor to
Monarch Governor Company, Detroit, Mich., a
corporation of Michigan

Application November 13, 1945, Serial No. 123,706

Term of patent 14 years

(Cl. D14—6)

To all whom it may concern:

Be it known that I, Lowell F. Sarnes, a citizen of the United States, residing in Dearborn, county of Wayne, State of Michigan, have invented a new, original, and ornamental Design for a Rear Vision Mirror or Similar Article, of which the following is a specification, reference being had therein to the accompanying drawing, forming a part thereof, in which

Fig. 1 is a plan view illustrating the back of a rear vision mirror or similar article embodying

a design in accordance with the present invention.
Fig. 2 is a side elevational view thereof.

The characteristic features of my design reside in the portions shown by means of full lines in the drawing.

I claim:

The ornamental design for a rear vision mirror or similar article, substantially as shown and described.

LOWELL F. SARNES.
